UNITED STATES PATENT OFFICE.

HENRY J. HEINZ, OF PITTSBURG, PENNSYLVANIA.

DESIGN FOR A BOTTLE.

SPECIFICATION forming part of Design No. 20,830, dated June 9, 1891.

Application filed January 30, 1891. Serial No. 379,702. Term of patent 14 years.

To all whom it may concern:

Be it known that I, HENRY J. HEINZ, of Pittsburgh, in the county of Allegheny and State of Pennsylvania, have invented a new and original Design for Bottles, of which the following is a full, clear, and exact description, reference being had to the accompanying drawings, forming part of this specification, in which—

10 Figure 1 shows in side view a bottle showing my design. Fig. 2 is a horizontal section on the line II II of Fig. 1.

The leading feature of my design consists in a bottle the lower part of which is polygonal in cross-section, having a series of parallel upright flat faces 2 extending about two-thirds of the distance to the top of the bottle, above which the bottle is circular in cross-section and conical in outline. At the

level *a a* the inclination of the sides becomes ²⁰ steeper, more nearly approaching the form of a cylinder.

In the drawings, 2 2 are the flat faces, and 3 4 are the upper portions, circular in cross-section. The extension of the faces 2 for a ²⁵ major portion of the length of the bottle, together with its large diameter in relation to the length, gives the bottle a peculiar and distinctive appearance.

I claim—

30 The design for bottles, substantially as herein shown and described.

In testimony whereof I have hereunto set my hand this 24th day of January, A.D. 1891.

HENRY J. HEINZ.
